UNITED STATES PATENT OFFICE.

ROBERT HOPE-JONES, DECEASED, LATE OF NORTH TONAWANDA, NEW YORK, BY CECIL HOPE-JONES, TEMPORARY ADMINISTRATRIX, OF NORTH TONAWANDA, NEW YORK, ASSIGNOR TO THE RUDOLPH WURLITZER MANUFACTURING COMPANY, OF NORTH TONAWANDA, NEW YORK, A CORPORATION OF NEW YORK.

PIANO-KEY MECHANISM.

1,301,267.

Specification of Letters Patent. Patented Apr. 22, 1919.

Application filed November 14, 1914. Serial No. 872,180.

To all whom it may concern:

Be it known that ROBERT HOPE-JONES, deceased, late of North Tonawanda, in the county of Niagara and State of New York, 5 did invent certain new and useful Improvements in Piano-Key Mechanisms, and the following is hereby declared to be a full, clear, and exact description of the same, reference being had to the accompanying drawings, forming a part of this specification, and to the reference - numerals marked thereon.

The present invention has for its object to provide means adapted to be connected to 15 a key or manual of the action of a musical instrument such as a piano, whereby the player may cause the power or force of the stroke to be increased. The invention further comprehends applying a yielding 20 mounting for the key, constituting a valve arranged to control air under pressure, which when released inflates a pneumatic or bellows adapted to act upon the inner end of the key to cause the thrust imparted by 25 it to the remaining portion of the key action to be greatly augmented. To these and other ends the invention consists in certain improvements and combinations of parts, all as will be hereinafter more fully described, 30 the novel features being pointed out in the claims at the end of the specification.

In the drawings:

Figure 1 is a detail view partly in section, showing a piano key action to which devices 35 illustrating one embodiment of the invention have been applied, and

Figs. 2, 3, and 4 are similar detail views illustrating modifications.

Fig. 5 is a fragmentary sectional elevation 40 of the key-pneumatic forming part of the modified arrangement shown in Fig. 4.

Similar reference numerals throughout the several views indicate the same parts.

Mechanism embodying the invention is 45 adapted to be applied to key operated musical instruments, and in the illustrations there is shown a piano key action comprising a key or manual 1 pivotally mounted above the bed 2, and upon the inner end of which 50 rests the jack 3, which it will be understood, is actuated upwardly to cause the hammer 4 to strike its respective string or strings 5. The mechanism for augmenting the touch

applied by the player to the outer end of the key is under the control of the player, and 55 generally described it comprises a yieldingly mounted valve member which may be depressed when the touch applied to the key is sufficient to overcome its normal resistance. This valve mechanism is preferably 60 arranged in conjunction with the pivot on which the key is mounted, and it controls passages leading from a pressure wind chest to a key pneumatic or bellows which, when inflated, acts upon the operating end of the 65 key to cause its upward movement.

In the form of the device illustrated in Fig. 1, showing one arrangement of the parts embodying the invention, the key 1 is pivoted on a rod 6 constituting a valve stem, 70 which is guided in brackets 7 and 8, and is provided with a collar 9 supporting the key 1, the parts being yieldingly supported by a coil spring 10 resting on the bracket 7. Beneath the key bed 2 and extending longitudinally thereof is a wind chest 11, which it will be understood contains air under pressure supplied from any suitable source, 75 Leading from the wind chest is a passage 12 which communicates with a key pneumatic 80 or bellows 13, having the outer or movable leaf provided with a push bar 14 which engages the lower side of the inner end of the key 1 when the latter is in its normal position, and the bellows 13 is deflated. The 85 passage 12 is provided with a port 12^a communicating with the wind chest 11, and with a vent 12^b opening into the atmosphere. The port 12^a is normally closed by the valve head 6^a, and another valve head 6^b is arranged on the valve stem 6 for the purpose of closing the vent 12^b when the stem 6 is depressed 90 sufficiently to reverse the normal conditions of said port and vent. Where a plurality of keys are arranged side by side, as in a piano action, the pneumatics 13 will be disposed beneath the key bed 2 in a plurality of horizontal rows, the pneumatics serving adjacent keys being in different rows and offset slightly to accommodate the rods 14. 100 In Fig. 1 there is shown a second pneumatic indicated by 13^a.

In practice the collar 9 is threaded on the valve stem 6 or other equivalent means is provided for adjusting the tension of the 105 spring 10, which normally supports the piv.

otal point of the key against vertical movement under all general requirements of a player or operator, as it is only intended to permit the key to be depressed bodily by a 5 rather pronounced attack, such as a player would apply when desiring particularly to strike a given note with more than the usual emphasis. The valve heads 6^a and 6^b are so adjusted relatively to each other that the 10 aperture 12^b will not be closed if the bodily downward movement of the key is a slow one, as would result if the player after depressing the outer end of the key should continue to apply pressure until the tension of 15 the spring 10 is overcome, as in this way the air pressure from the wind chest 11 entering the port 12^a would become equalized and fail to operate the key pneumatic by reason of the opening through the vent 12^b. The adjustment 20 of the two valve heads is also such that upon a sudden downward movement of the pivotal point of the key the vent is closed and the port is opened, whereupon the air pressure entering the bellows 13 operates its 25 pusher 14 upwardly to impart to the inner end of the key 1 a force which is considerably greater than that which it is capable for the operator to create by manually depressing the outer end of the key.

30 In Fig. 2 a modified arrangement of the mechanism is illustrated, showing a key or digital 15 pivoted on a rod 16 yieldingly supported on a leaf spring 17 carrying a valve head 18 in a wind chest 19, connected by a 35 passage 20 with a key pneumatic 21. The valve head is provided with a passage 18^a which, when said head is depressed, opens communication between the wind chest and the passage 20, and on the under side of the 40 valve head is a recess 18^b which, when the valve head is in its normal position, permits the escape of air from the passage 20 by connecting it with a vent 22. In the structure shown in Figs. 1 and 2, the only resistance 45 against the downward bodily movement of the key is that afforded by the springs 10 and 17, and in Figs. 3, 4 and 5 there are shown modifications of the invention in which the air pressure may be utilized to assist in holding the key pivot in its normal position. In 50 one instance the valve member itself is acted upon by the air pressure to resist the movement of the key, while in the other form the valve head is connected to a bellows which 55 performs this function.

In Fig. 3, the key 23 is balanced on the valve rod 24 which carries at its lower end a cylindrical valve head 25 guided vertically in a casing 26 preferably located in the wind 60 chest 27. The valve head 25 and its casing 26 are provided respectively with a plurality of apertures 25^a and 26^a, which are so disposed relatively to each other that the apertures are normally closed, as shown in Fig. 65 3, the key and valve head being sustained

lightly in this position by means of the leaf spring 28. The pipe or passage 29 leads from the bottom of the casing 26 to the key pneumatic 30, provided with a push rod 31 bearing against the bottom of the key 23. 70 In this form of apparatus the key need only be lightly supported by the spring 28, as any tendency to a downward movement of the pivotal point of the key will be checked sufficiently by the resistance caused by the air 75 pressure in the wind chest 27, entering the ports 26^a, 25^a, but which does not become fully effective to influence the movement of the bellows 30 until a sufficiently decided downward movement of the key has occurred 80 to cause the valve openings to fully uncover the ports 26^a.

In Figs. 4 and 5 the results last described are accomplished by using a bellows 32 disposed in a chamber 33 from which leads a 85 passage 34 to the key pneumatic 30^a. The chamber 33 is connected with the wind chest 35 through an aperture 35^a which is opened and closed by a valve head 36 having a port 36^a. The valve head 36 is connected to the 90 bellows 32 by a stem 37, the upper end of which bears against a light leaf spring 38 on which rests the pivot 39 of the key 40. The bellows 32 is partially distended, and a slow leakage of air from the wind chest 35 into 95 the chamber 33 will tend to cause its collapse, thus holding the stem 37 against the spring 38, the upward movement of which is limited by the stop 41. If the key 40 is suddenly depressed the flow of air through port 36^a and aperture 35^a will be sufficient to enter the 100 passage 34 to actuate its respective key pneumatic 30^a at the same instant it acts upon the bellows 32 to restore the pivotal point of the key. 105

A device constructed in accordance with the invention, provides a simple means for assisting the movement of the keys of a musical instrument, whereby the player can obtain a wider range of expression in his playing, and it also possesses the further advantage that the loud or accented notes which are to be struck can be sounded without taxing the physical force of the player. 110

The claim of the invention is:

1. The combination with the key of a musical instrument, the mechanism operated thereby and a power device also adapted to impart movement to said mechanism, of a yieldable fulcrum for the key controlling 120 the action of the power device.

2. The combination with the pivoted key of a musical instrument, and the action operated by the normal rocking movement of the key, of an auxiliary power device for 125 imparting movement to the action means yieldingly supporting the key pivot controlling the operation of said power device and actuated by the depression of the key pivot.

3. The combination with the pivoted key 130

- of a musical instrument, the action operated thereby and a normally inactive auxiliary device adapted to apply a powerful movement to said action, of a controlling member 5 for said auxiliary device arranged to yieldingly support said key and moved to actuate said auxiliary device upon the depression of the key pivot.
4. The combination with the key of a 10 musical instrument, the action operated thereby and a yieldingly supported pivot member for the key, of a source of power, a motor adapted to impart movement to the action and means operated by the movement 15 of the pivot member for connecting said source of power and motor.
5. The combination with the key of a 20 musical instrument and the action operated thereby, of an auxiliary power device for imparting movement to the action, and means governed by the movement of the key for effecting the conjoint operation of said key and power device upon the action.
6. The combination with the key of a 25 musical instrument, an action operated thereby and a wind chest, of a pneumatic device also adapted to operate said action and a valve having a fixed resistance to its opening movement and adapted to be opened by
- the depression of the key with force sufficient 30 to overcome such resistance and arranged to control the passage of fluid from the chest to the pneumatic device.
7. The combination with a piano action comprising a key, an action operated thereby, a pneumatic motor also arranged to operate the action and a wind chest, a valve for connecting the wind chest and motor and yieldingly supporting the key against the normal pressure applied thereto and to move 40 into open position to effect the operation of the motor conjointly with the key when the latter is actuated by an abnormal pressure.
8. The combination with a piano action comprising a key, of a vertically movable 45 support on which the key is pivoted, a pneumatic motor adapted to impart movement to the action, a wind chest comprising a passage communicating with the motor, a valve controlling said passage and a spring sus- 50 taining the key support and yieldingly holding the valve in closed position.
